Primary Examiner — Barbara Fox(74) *Attorney, Agent, or Firm* — NSIP Law(57) **CLAIM**

We claim the ornamental design for an electronic device, as shown and described.

DESCRIPTION

FIG. 1 is a front perspective view of an electronic device showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a rear perspective view thereof.

The broken lines shown in the drawings depict portions of the electronic device that form no part of the claimed design.

1 Claim, 6 Drawing Sheets(56)
